ELECTRODE MOUNTING ARRANGEMENT

Thomas G. Crawford, Glenville, N. Y., assignor to
General Electric Company, a corporation of
New York

Application September 19, 1940, Serial No. 357,424

4 Claims. (Cl. 250—27.5)

The present invention relates to an improved electrode mounting arrangement for electric discharge devices. While not limited thereto, the invention is especially applicable in connection 5 with high frequency power tubes.

Tubes of the character referred to generally employ a cathode which is made up of a plurality of separate elongated filaments positioned in closely spaced relationship to other parts of 10 the tube structure, such as the grid. With this arrangement there is a danger that short-circuiting may occur as a consequence of uncompensated expansion of the cathode filaments. This 15 danger has been found to be especially great in connection with tubes in which the cathode heating current is supplied to the various filaments from a polyphase source which is subject to unbalanced operation. Under these circumstances, the individual filaments may be heated to different 20 degrees so that the resultant unequal expansion of the filaments tends to cause distortion of the cathode structure and breakage of its parts.

It is an object of the present invention to provide a cathode mounting which eliminates the 25 expansion difficulties outlined in the foregoing. In a broad sense, this is accomplished by providing each of the cathode filaments with a separate tensioning assembly. It is considered, however, that the more important aspect of the invention 30 consists in a particular form of assembly which assures satisfactory operation under extreme conditions and which permits the attainment of a long life under such conditions.

The features which I desire to protect herein 35 are pointed out with particularity in the appended claims. The invention itself, together with further objects and advantages thereof, may best be understood by reference to the following description taken in connection with the drawing in 40 which Fig. 1 is a longitudinal sectional view of an evacuated discharge device suitably embodying the invention; Fig. 2 is an enlarged detail view of the cathode arrangement shown on a smaller scale in Fig. 1; Fig. 3 is a section taken 45 on line 3—3 of Fig. 2; and Fig. 4 is a sectional view of one of the mounting element of Fig. 2, showing the same as it appears when the associated cathode filament is in fully expanded condition.

50 Referring particularly to Fig. 1 there is shown a discharge device comprising an elongated cylindrical anode 10 which consists, for example, of copper and which constitutes a portion of the enclosure of the device. The anode is provided 55 with an outwardly extending flange 11 to facili-

tate its assembly with a water jacket or other means for cooling the exterior anode surface.

Within the anode and arranged coaxially therewith there is provided a separately heated cathode comprising a plurality of filaments 13 which are arranged in hollow configuration. These filaments are in turn surrounded by a grid structure which is shown as comprising grid wires 15 wound helically on a plurality of stay rods 16 which parallel the filaments 13. For high frequency operation the grid is preferably arranged very close to the cathode structure so that the spacing between the grid wires and the cathode filaments may be on the order of 0.180 inch.

The open end of the anode is hermetically 15 joined to a glass envelope 17 which serves to seal the discharge space between the anode and cathode. The envelope is provided with an insulating base 19 which is held in place by means of a flanged metal member 20 cemented to the 20 envelope. The base 19 serves to support a series of terminal elements 22 which are respectively associated with lead-in conductors 23 for the various cathode filaments. A duct 24 extending through the base serves as an inlet for a 25 cooling fluid, such as air, which may be introduced to maintain the end of the envelope at a safe temperature.

Within the enclosure formed by the envelope 17 there is provided a glass sleeve 26 which extends 30 toward the anode 10 and to which there is secured a flanged metal sleeve 27. The sleeve 27 serves as a mounting element for the grid structure which is secured thereto through the agency of a second flanged ring 28. This second ring is 35 connected directly to extensions of the grid stay rods 16 and is in clamped engagement with an annular disk member 30 to which a lead-in conductor 31 for the grid is secured. The conductor 31 is provided with an externally accessible grid 40 terminal 32. Concentric with the sleeve 26 there is provided a reentrant circular press 35. This serves as a mount for a plurality of fixed terminals 37 which are connected outside the envelope 45 with the current supply conductors 23. The various terminals 37 are supported in rigid assembly by means of an apertured metal disk 40 which embraces the various terminals but which is insulated therefrom by a plurality of insulating sleeves 41, suitably consisting of quartz. This 50 disk also engages and serves as a partial support for a fixed rod 42 which forms the central stem of the cathode structure and from which all the cathode filaments are supported at the end of the envelope which is remote from the stem 55

press 35. The supporting connection between the filaments and the rod 42 is made through a metal disk 43 which peripherally engages the various filaments. The filaments are held in 5 contact with the disk 43 by being welded together at their extremities as indicated at 44. In the intended use of the device in connection with a multiphase cathode current supply, the point 44 represents the neutral point of the 10 cathode so that no current connection for the rod 42 is required.

As appears most clearly in Fig. 2, each of the fixed terminals 37 is fitted with a metallic sleeve 46 which extends from the terminal toward the 15 other extremity of the envelope. Each of the sleeves has in the end which is remote from its associated terminal an apertured disk 46' with an opening of sufficient size to receive loosely a member 47 constituting an extension of one 20 of the cathode filaments. The members 47 are held in appropriately spaced relationship by means of insulating eyelets 48 which abut the extremities of the various sleeves and which engage the members with sufficient clearance to 25 permit their axial motion. The eyelets 48 are mounted on an apertured disk 49 which is secured centrally to the cathode rod 42.

As is illustrated by the sectional sleeve of Fig. 30 2, each of the filament extensions 47 terminates in a disk 50 which slidably engages the inner surface of the sleeve so as to be capable of longitudinal movement therein and which furnishes a 35 guide for the member to which it is secured. A compression spring 51 arranged within the sleeve 46 bears on the under surface of the disk 50 and thus serves to maintain the connected filament 40 under tension. A flexible connection between the guiding disk and the fixed terminal 37 is provided by means of a number of helically formed 45 braided conductors 53 which may suitably be constituted of copper. These conductors are capable of considerable extensive and compressive movement so that an appreciable expansion of the cathode filaments may occur without danger 50 of breaking the current supply path.

The operation of the cathode tensioning means is best shown in Fig. 4 which illustrates the 55 condition of one of the springs 51 and the associated conductors 53 when the filament connected therewith is in its fully expanded condition. It will be noted that under these circumstances, the various turns of the conductor 53 have become closely compacted while the turns of the spring 51 have opened due to their 60 longitudinal expansion.

An arrangement of the kind specified possesses the advantage that it permits unequal expansive movements of the various cathode filaments to occur without thereby causing any distortion of 65 the cathode structure as a whole. As has been previously pointed out, this is a consideration which is especially important in cases where the various filaments of the cathode are to be supplied from a polyphase current source. In numerous instances a temporary unbalancing of the phase voltages of such a source may cause a 70 serious discrepancy in the amount of heating of the various filaments and may thus cause certain filaments to expand a great deal more than others. The arrangement described in the foregoing permits this action to occur without actually warping the cathode structure or disturbing the spatial relationship between the cathode filaments and the grid structure.

75 The particular arrangement specified, wherein

each of the filament tensioning means is enclosed within a separate metallic sleeve, has the advantage that the various springs and flexible conductors are well protected from heat generated within the discharge space and also from the 5 occurrence of excessive heating during the exhaust procedures to which devices of the character under consideration are ordinarily subjected. Moreover, this arrangement provides a compact construction and one which may be relied upon to have a long operating life even 10 under very adverse conditions of operation.

While the invention has been described by reference to a particular embodiment thereof, it will be understood that numerous modifications 15 may be made by those skilled in the art without departing from the invention. I therefore, aim to cover in the appended claims all such equivalent variations as come within the true spirit and scope of the foregoing disclosure.

What I claim as new and desire to secure by Letters Patent of the United States is:

1. An electric discharge device comprising an anode, a cathode consisting of a plurality of elongated filaments, an envelope hermetically sealing the discharge space between the anode and cathode, a plurality of lead-in wires extending within the envelope and having fixed terminals therein, and a plurality of mountings for separately tensioning the various cathode filaments, each said mounting including an elongated sleeve, means comprising an extension of one of the said filaments projecting into the sleeve so as to be longitudinally movable therein, a compression spring within the sleeve and acting to maintain the said filament under tension, and a conductor also within the said sleeve and providing a flexible connection between the said filament extension and one of the said fixed lead-in terminals.

2. An electric discharge device comprising an anode, a cathode consisting of a plurality of elongated filaments, an envelope hermetically sealing the discharge space between the anode and cathode, a plurality of lead-in wires extending within the envelope and having fixed terminals therein, and a plurality of mountings for separately tensioning the various cathode filaments, each said mounting including an elongated sleeve connected with and forming an extension of one of the said lead-in terminals, means comprising an extension of one of said filaments projecting into said sleeve at the end thereof which is remote from the said lead-in terminal, a spring within the said sleeve and tending to move the said filament extension toward the said terminal so as to maintain the filament under tension, and a conductor within the sleeve providing a flexible connection between the filament extension and the said lead-in terminal.

3. An electric discharge device comprising an anode, a cathode consisting of a plurality of elongated filaments, an envelope hermetically sealing the discharge space between the anode and cathode, a plurality of lead-in wires extending within the envelope and having terminals therein, and a plurality of mountings for separately tensioning the various cathode filaments, each said mounting including an elongated sleeve connecting at one end with one of the said terminals, means comprising an extension of one of the said filaments projecting into the sleeve at the end thereof which is remote from the said terminal, means slidably engaging the interior of the said sleeve for guiding the motion of the said filament extension

5 therein, a spring within the sleeve for urging the said filament extension toward the said terminal so as to maintain the filament under tension, and a readily deformable conductor extending longitudinally of the said sleeve between the filament extension and the lead-in terminal for providing a flexible connection between them.

10 4. An electric discharge device comprising an anode, a cathode consisting of a plurality of elongated filaments, an envelope hermetically sealing the discharge space between the anode and cathode, a plurality of lead-in wires extending within the envelope and having terminals therein, and a plurality of mountings for separately 15 tensioning the various cathode filaments, each said mounting including an elongated sleeve con-

necting at one end with one of the said terminals, means comprising an extension of one of the said filaments projecting into the sleeve at the end thereof which is remote from the said terminal, means slidably engaging the interior of the said sleeve for guiding the motion of the said filament extension therein, a spring within the sleeve for urging the said filament extension toward the said terminal so as to maintain the filament under tension, and a helically formed 10 braided conductor within the said sleeve for providing a flexible connection between the said filament extension and one of the said fixed lead-in terminals.

15 THOMAS G. CRAWFORD. 15
